UNITED STATES PATENT OFFICE

2,456,341

SIREN TOP

Oscar Thoresen, Pittsburgh, Pa.

Application October 3, 1946, Serial No. 700,962

4 Claims. (Cl. 46—66)

1

This invention pertains to a sound producing toy top and more particularly, to a siren top.

It has been an object of my invention to provide a new and improved form of top capable of producing sound during its rotation.

Another object has been to provide a simple, inexpensive and efficient form of siren top.

A further object has been to provide a top having at least two parts capable of relative motion with respect to each other, having passageways therethrough for producing sound effects, and having a relatively low coefficient of friction with respect to each other.

A still further object has been to devise a top having a low center of gravity and capable of spinning for a long period of time.

These and many other objects of my invention will appear to those skilled in the art from the description of the exemplary embodiments thereof, as well as from the appended claims.

In the drawings:

Figure 1 is a side view in elevation of an exemplary form of top illustrating my invention;

Figure 2 is a top plan view of the toy top of Figure 1;

Figure 3 is a vertical sectional view in elevation taken along the line III—III of Figure 2;

Figure 4 is an exploded view in elevation of the top shown in Figures 1 to 3, inclusive;

Figure 5 is a top view, partially in section, taken along the line V—V of Figure 3;

Figure 6 is a vertical section, similar to Figure 3, but showing a modified form of my invention;

Figure 7 is a perspective view in elevation of a vane element used in the embodiment of Figure 6.

In the embodiment of my invention shown in Figures 1 to 5, inclusive, I have provided a lower body or housing portion 10, an upper cover body portion 15 constructed and arranged to be rotated by a shaft 25. The shaft 25 is journaled within the upper and lower body portions 15 and 10, see particularly Figures 3 and 5.

As shown particularly in Figure 3, the lower body portion 10 is provided with a rounded off spinner tip or insert 11 secured thereto and mounted thereon for rotation therewith, and a series of air passages or holes 13 about the periphery of side walls thereof. The upper or cover lid portion 15 is provided with downwardly extending lip portions having a removable friction fit with the side walls of the lower body portion 10 to provide a substantially complete enclosing housing body. An upper face of

2

the cover portion 15 is provided with a plurality of air passages or holes 16 through which fluid may enter the inside of the top to produce sound effects. The center of the body 15 is drilled out to receive the shaft 25 and provided with a bearing housing 17 which may carry ball bearings 18 and an inner sleeve race 19. The race 19 is rotatably mounted about portion 27 of the shaft 25.

10 The upwardly-open cup-shaped rotor portion or element 20 has an upwardly, centrally-extending hub portion 21 that is drilled out to securely receive mounting portions 28 and 29 of the rotating shaft 25 in such a manner that the rotor 20 will turn with the shaft 25. The rotor 20 is provided with upwardly-extending side walls that are slightly spaced apart from the side walls of the lower body 10 and have a series of holes or passageways 22 about the periphery thereof, 20 preferably in substantial alignment with the holes 13 of the body 10.

The rotating stem 25 has a knurled portion 26 for winding a string or cord thereabout, a portion 27 that is rotatably carried by the ball bearing assembly 17, and a lower end 30 that is rotatably carried by a thrust bearing opening in the spinner or downwardly projecting tip element 11.

25 The top may be actuated by winding a piece of string about the knurled portion 26. Rotation may be prevented during the winding operation by holding the upper portion of the stem 25 or by inserting a pin or stick through a pair of registering passageways 13 and 22. When the string is quickly pulled off the knurled portion 26, the rotor 20 will have a high speed of rotation and air will be forced by centrifugal action through passageways 16 into the inside of the rotor 20, out through passageways 22 and 13 to produce a siren-like sound effect.

30 Due to the low coefficient of friction, the top has a long continued, high speed rate of spin. The relative rotation between the rotor 20 and the outer body 10 aids the sound effect. The low center of gravity of the top increases its effectiveness and efficiency. Since the shaft 25 does not directly engage the floor, but engages it indirectly through the tip 11, which may be an integral part of 10 or an insert, the length of 35 rotative movement is further enhanced.

35 In Figures 6 and 7, I have shown a modified embodiment of my invention in which the parts 10, 15 and 25 may be constructed substantially the same as in the previous embodiment. However, I provide an additional element 31 which,

as shown particularly in Figure 7, has a central mounting hole 32 permitting it to fit over the hub 21 of the rotor 20, and outwardly extending vane supporting portions 33 which cooperate with upwardly extending walls of the rotor 20, see Figure 6. A series of spaced apart, vertically-upset or upwardly extending vanes or wall portions 34 extend from the support portions 33 to provide segregated fluid chambers within the rotor 20. The auxiliary element 31 is preferably mounted so it will rotate with the rotor 20. When used, it increases the weight of the top slightly; it may be employed to change the sound effect by reason of the increased complexity of the air passages thereby provided, and also, by turning it about the hub 21 to change its relative position within the rotor 20.

In the preferred form of my invention, the element 11, the shaft 25, and the bearing assembly 17 are of metal construction. The other parts, such as the housing 10-15, the rotor 20, and the element 31, may be of wood, plastic, glass, or metal construction. Of course, it will be apparent that the immediate bearing surfaces only may be of metal or of any suitable hard material construction and the other portions may be of any suitable material.

Referring particularly to the preferred embodiment of my invention shown in Figures 1 to 5 inclusive, it will be noted that the siren top is provided with an outer spinner housing made up of two parts namely, 10 and 15. Such outer housing has a vertical side wall portion and a pair of opposite and spaced-apart substantially horizontal top and bottom wall portions which inclose and define a primary chamber of substantially circular contour. One of the pair of the horizontal wall portions, see Figure 2, is provided with a series of spaced-apart openings 16 therein or therethrough for introducing air into the primary air chamber. An opposite horizontal wall portion, see the bottom portion of Figure 3, is provided with a spin tip 11 which is secured thereto substantially centrally thereof to rest upon a surface about which the top is to be spun.

The rotor shaft 25 extends between the pair of horizontal wall portions and is journaled therein. It will be noted that the shaft 25 also extends through a horizontal wall portion that is opposite the wall portion on which the spin tip 11 is secured. The cup-shaped inner housing or rotor 20 is open on one of its horizontal sides or faces and is provided with a horizontal wall portion and a substantially circular-shaped, vertical wall portion which define a secondary air chamber within the primary chamber of the outer housing. It will be noted that the open horizontal side faces the horizontal wall portion of the outer housing which is provided with the spaced-apart, air-introducing holes or passages 16.

The inner, cup-shaped housing or rotor 20 is securely mounted on the shaft 25 for rotation therewith, and for relative rotation with respect to the outer housing. The side wall portions of both the outer and inner housings of the top are provided with a series of spaced-apart holes or openings 13 and 22 therethrough, and about their respected peripheries which provide outlets from the secondary air chamber when they are in alignment. It will be noted that the holes 13 and 22 are on substantially the same horizontal plane, and due to the relative rotation between the inner and outer housings, produce desired siren sound effects. That is, when the shaft 25 is spun by means of a string, for example, rotation

is directly imparted to the inner housing 20, and is indirectly imparted through the shaft bearings to the outer housing 10-15. The small amount of friction in the bearings effects rotative movement of the outer housing, but at a much slower rate than that of inner housing. Another feature of importance is the low center of gravity of the over-all construction; in addition to its contour, the overlapping, mounted relationship of the top wall portion 15 on the side wall portion of the lower half 10 of the outer housing is important in this connection.

Although for the purpose of illustrating my invention I have shown exemplary embodiments thereof, it will be apparent to those skilled in the art that various substitutions, subtractions, revisions, and modifications may be made thereto without departing from the spirit and scope thereof as indicated by the appended claims.

20 What I claim is:

1. A siren top comprising, an outer spinner housing having a two-part interfitting construction, said outer housing having a substantially vertical side wall portion and a pair of spaced-apart and substantially horizontal wall portions defining a substantially circular primary air chamber therein, one of the horizontal wall portions of said outer housing having a series of spaced-apart holes therethrough for introducing air into said primary chamber, one of the horizontal wall portions of said outer housing having a spin tip rigidly secured thereto and extending substantially centrally-downwardly therefrom; a rotatable shaft extending between the horizontal wall portions of said outer housing and being substantially centrally journaled therein, said rotatable shaft having an upper length extending vertically above the horizontal wall portion of said outer housing that is opposite to the horizontal wall portion having said spin tip; a cup-shaped inner housing securely mounted on said rotatable shaft within said outer housing, said inner housing having a horizontal wall portion and a vertical side wall portion defining a secondary air chamber therein, the side wall portion of said inner housing terminating opposite to the horizontal wall portion thereof in a horizontal portion open to said primary air chamber, said inner housing being mounted on said rotatable shaft with its horizontal open portion in vertical alignment with and facing the spaced-apart holes through one of the horizontal portions of said outer housing; the side wall portion of said inner housing having a series of holes therethrough and in a spaced-apart relationship thereabout and entrant to said secondary air chamber; the side wall portion of said outer housing having a series of holes therethrough and in a spaced-apart relationship thereabout and entrant to said primary air chamber; the holes through said inner and outer housings being located on substantially the same horizontal plane with respect to each other to exhaust air from said secondary air chamber when they register with respect to each other; said rotatable shaft being constructed and arranged to directly actuate said inner housing and to indirectly actuate said outer housing through the journaling of said rotatable shaft to rotate said outer housing at a relatively lower speed than said inner housing.

2. A siren top as defined in claim 1, wherein, the upper length of said shaft has a knurled portion for receiving a winding string and has a smooth end portion for holding said shaft during the string winding operation and while the string

is being pulled off said knurled portion to spin the top.

3. A siren top as defined in claim 1 wherein, the horizontal wall portion of said outer housing that has the series of spaced-apart holes provides a top portion for the top and is provided with a ball-bearing race for journaling said shaft therein, the horizontal wall portion of said outer housing that has the spin tip provides a bottom portion for the top, said spin tip at one end extends into a central opening in said last-mentioned wall portion and is provided with a thrust bearing for journaling a lower end of said shaft, and the open portion of said inner housing faces upwardly thereof.

4. A siren top as defined in claim 1 wherein, a vane element is mounted within said inner housing for rotation therewith, said vane element being provided with a series of spaced-apart and

vertically-extending wall portions to provide segregated fluid chambers with said inner housing.
